UNITED STATES PATENT OFFICE.

CHARLES A. GARRETT, OF PHILADELPHIA, PENNSYLVANIA.

MACHINE FOR PRINTING AND FORMING CAPS FOR CONTAINERS.

1,365,679.

Specification of Letters Patent. Patented Jan. 18, 1921.

Application filed June 4, 1920. Serial No. 386,650.

To all whom it may concern:

Be it known that I, CHARLES A. GARRETT, a citizen of the United States, residing at Philadelphia, in the county of Philadelphia and State of Pennsylvania, have invented 5 an Improved Machine for Printing and Forming Caps for Containers, of which the following is a specification.

My invention is designed especially for 10 providing printed caps for receptacles by feeding sheets or sheeted strips of suitable material, generally paper, through a printing mechanism by which impressions are printed at regular intervals, and in sequence 15 therewith through a forming mechanism by which the printed sections are successively died out and pressed to shape, mechanism being provided for perforating the sections that are to be died out and pressed to shape 20 when perforated caps are desired, as for boxes containing powder which it is desired to sift therefrom.

In the accompanying drawings, Figure 1 is a broken front elevation of a machine embodying my improvements; Fig. 2 is a side elevation of the same; Fig. 3 is a broken plan view taken on the line 3^x—3^x of Fig. 1; Fig. 4 is a sectional view taken on the line 4^x—4^x of Fig. 3; and Fig. 5 is a sectional 30 view taken on the line 5^x—5^x of Fig. 3.

In the form of the invention illustrated in the drawings, a frame 1 is provided with a vertical guide 2 for a die block 3 which is reciprocated in the guide by the crank shaft 35 4 through the connecting rods 5, the shaft being driven by a belt wheel 6. The block 3 is provided with a cutting die 7 and a male forming die 8, disposed concentrically with the die 7, the die 8 being movable relatively 40 to the die 7 by the pitman 9 connected with the crank shaft 4. The hollow base 10 is provided with the female die 11 disposed concentrically with relation to the dies 7 and 8 and with which said dies coact to cut and 45 form sheet material fed over the die 11 beneath the stripper 12, which is secured there-to to prevent the rise of the sheet with the dies after the cutting and forming operations have been completed, the caps thus 50 formed being delivered to the chute 13 whence they are discharged from the machine. This construction is of known character.

In accordance with my invention, a sheet 55 14 of paper board is fed over a table 15 and straps 15' beneath a stationary platen 16

and between the guides 17 over the female die 11, intermittently by the friction strips 18 and 19 together with the blocks 20 to which they are fixed. The blocks 20 are reciprocated by a rocking cam link 21 connected thereto by the pin 22 and connected by a link 23 with the crank arm 24 on a shaft 25 journaled in the bearing 26. The shaft 25 is rocked by an arm 27 fixed thereon and 60 connected through the flexible coupling 28 with a link 29 which is connected flexibly with a coupling or collar 30 in which is journaled a stud 31 on a block 32 adapted to be set by a screw 33 in a radial guide 34 of an 65 arm 35 fixed on the shaft 4. The coupling 28 is connected with the parts 27 and 29 respectively by the pins 36 and 37 disposed at right angles to each other and the part 29 is connected with the part 30 by the pin 38 at 70 right angles to the stud 31, to provide the desired flexibility of movement for transforming the rotary movement of the stud 31 to the rocking movement of the shaft 25 at right angles thereto. A coiled spring 29^a 80 connects the parts 2 and 29, to draw the latter transversely and prevent lost motion in the connected parts.

A cross bar 39 having journals 40 adapted to rock in the bearings 41, is provided with 85 an inclined dog 42 held in engagement with the paper strip 14 between the friction strips 18 by a spring 43, which connects a projection 44 on the cross bar 39 with the stationary part or anchor 45, the dog being able to 90 rock against the action of the spring to permit the paper to be drawn forward thereunder and being held by the spring in engagement with the paper to prevent the latter from being moved backward upon the 95 retraction of the parts 18, 19 and 20.

The blocks 20 are provided with the plate 46 having thereon the downwardly extending projections 47 for engaging the paper, the plate being supported by the springs 48 100 for holding it normally in the elevated position or at the top of its guides 49 in the blocks 20.

When the cam link 21 is operated to draw back the blocks 20 with the connected parts, 105 the toe 21' of this link or lever is elevated and the plate 46 is held by the springs 48 in elevated position out of engagement with paper. But in the forward movement, the link 21 is rocked on the pin 22 toward the 110 vertical, and the toe 21' depresses the plate 46 so that the projections 47 engage the

paper, which is carried forward therewith without possibility of slipping or lost motion. At the limit of the forward movement, the cam link or lever 21 is drawn back 5 so as to disengage the plate 46, which now rises and is disengaged from the paper, the latter being held in position by the dog 42 so that the paper is moved the desired distance and held in position with avoidance of 10 objectionable movements.

A printing block or form 49 is carried by an arm 50 which is connected with an arm 51, the lever formed by these arms being fulcrumed on the bearing 52. The arm 51 is 15 provided with a laterally projecting member 53 which is connected by a link 54 with a toggle link 55 having a slot 56 therein through which and the link 54 passes a bolt 57 adjustable along the slot to vary the 20 throw of the toggle link. The link 55 is fulcrumed on a bearing 58 and is connected by a pin 59 with a link 60, the latter being connected by a bearing 61 with the block 62 adapted to reciprocate in the way 63. A 25 bifurcated lever 64 is fulcrumed on the bearings 65 carried by the block 62 and bears at its rear on a spring 66 supported by the block. The lever 64 carries an inking roller 67 adapted to be moved, by the reciprocations of the block 62, alternately in contact 30 with the printing form 49 and the ink roller 68 which revolves in the ink fountain 69, the spring 66 acting to press the roller 67 against the printing form 49 and the roller 68. It 35 will be understood that the form 49 is held in the relation to the roller 68 shown in Fig. 4 as the roller 67 passes between the parts 49 and 68.

The arm 51 is rocked, to operate the parts 40 49 and 67 in synchronous relation, by the toggle link 70, connected by the pin 71 with the arm, and the toggle lever 72 connected by the pin 73 with the fixed bearing 74, the parts 70 and 72 being connected by a pin 75 45 with an adjustable head 76 on the connecting rod 77 having a head 78 thereon. An arm 79, fulcrumed on a bearing 80, is connected by a pin 81 with the head 78 and reciprocates the rod 77 to operate the links 70 and 72. The arm 79 is adapted to be rocked 50 by an arm 82, which is fulcrumed on the bearing 80 and is provided with a bolt 83 movable in the guide 84 thereof into and out of engagement with the notch 85 of a disk 86 forming the hub of the arm 79. The bolt 83 is reciprocated by a lever 87 which is 55 fulcrumed on a bearing 88 and provided with a slot 89 engaging a stud 90 on the bolt 83. The arm 82 is rocked by a rod 91 having the bearing 92 through which and the slot 93 in the arm passes a bolt 94 adjustable in the slot, the rod being connected with a strap or collar 95 on an eccentric 96 which is fixed to and revolved by the shaft 4. 60

65 A pulley 97 on the shaft 4 drives a belt

98 which passes therefrom over a pulley 99 driven thereby. The pulley 99 has fixed thereto a pulley 100 over which passes a crossed belt 101 to a pulley 102 driven thereby, the latter being fixed on a shaft 103 journaled in the bearing 104 and having fixed thereon a sprocket wheel 105. A chain 106, passing over and driven by the wheel 105, drives a sprocket wheel 107 on a shaft 108 which is journaled in a vertically adjustable 70 bearing 109. A spur wheel 110 fixed on the shaft 107 engages a spur wheel 111 fixed to the ink roller 68 which is revolved thereby 75 in the fountain 69.

A lever 112 is rocked on a stationary fulcrum 113 by the engagement of the lever with a stud 114 passing through the slot 115 therein and fixed to the die block 3, the lever being connected by a pin 116 to a block 117 movable under control of the vertical guides 80 118, the block being provided with the pins 119 for puncturing sheet material as it stands thereunder between the guides 17 in its intermittent movement to the dies. 85

It will now be understood that in the operation 90 of the machine, the rotating crank shaft 4 operates the dies 7 and 8 through the described intermediate mechanism together with the feeding mechanism comprising the device 20 with the connected parts through 95 the described intermediate mechanism, and the printing mechanism comprising the form 49 with its connected parts through the described intermediate mechanism, all in synchronous relation, so that the paper 14 is fed 100 forward step by step between the printing members 16 and 49 and between the forming members 7-8 and 11. Successive sections of the sheet are printed between the steps of the feeding operation and the printed sections are died out and pressed to form 105 between the steps of the feeding operation, the printed sections being perforated by the device 119 (when connected in operating relation) between the steps of the feeding operation 110 as such sections pass from the printing to the forming mechanism.

Having described my invention, I claim:

1. In a machine of the character described, the combination with a cap forming mechanism and stock feeding mechanism adapted for carrying a sheet of material step by step to said cap forming mechanism, of a printing mechanism adapted for printing successive sections of said sheet 115 while stationary between its step by step movements, said printing mechanism comprising a stationary plate under which said sheet is carried on its way to said forming mechanism, an oscillatory printing form 120 above which said sheet is carried on its way to said forming mechanism, means comprising an arm provided with an inking roller 125 for inking said form, a slide to which said arm is pivotally connected, and means con- 130

nected with said forming and feeding mechanisms for oscillating said printing form and reciprocating said slide to ink said printing form in a lowered position thereof and alternately therewith to elevate said form and print said sheet, in synchronous relation with the operations of said forming and feeding mechanisms.

2. In a machine of the character described, the combination with a cap forming mechanism and stock feeding mechanism adapted for carrying a sheet of material step by step to said cap forming mechanism, of a printing mechanism adapted for printing successive sections of said sheet while stationary between its step by step movements, said printing mechanism comprising a plate and an oscillatory printing form between which said sheet is carried in its passage to said forming mechanism, ink supply mechanism, a reciprocatory slide, oscillatory means comprising an inking roller fulcrumed on said slide, and means connecting said printing form and slide whereby they are operated in synchronous relation to move said inking roller over said form to and from said ink supply mechanism and alternately therewith to operate said form.

3. In a machine of the character described, the combination with a cap forming mechanism and marking mechanism, of stock feeding mechanism adapted for carrying a sheet of material step by step to said marking and cap forming mechanisms, said feeding mechanism comprising a reciprocatory device, gripping means carried by said device for engaging and feeding a sheet of stock to said forming mechanism, means for automatically withdrawing said gripping means from said sheet and means for reciprocating said device comprising mechanism for depressing said gripping means to engage said sheet in the forward feeding movement of said device.

4. In a machine of the character described, the combination with a cap forming mechanism and a marking mechanism, of stock feeding mechanism adapted for carrying a sheet of material step by step through said marking and forming mechanisms, said feeding mechanism comprising a reciprocatory member provided with a gripping device adapted to be pressed into engagement with said sheet and to be automatically disengaged therefrom and means for operating said reciprocatory member, said last named means comprising a lever connected in rocking relation with said member and mechanism whereby said lever is rocked in one direction to effect the engagement of

said device with said sheet in the forward feeding movement of said member and is rocked in the opposite direction so as to disengage said device in the rearward movement of said member.

5. In a machine of the character described, the combination with a revoluble shaft, die mechanism reciprocated thereby, printing mechanism operated thereby and stock feeding mechanism operated thereby to carry a sheet of material step by step to said printing and die mechanisms, said stock feeding mechanism comprising a reciprocatory device provided with frictional members and a gripping member for engaging a sheet of paper to feed the same forward, means for automatically disengaging said gripping member from said sheet of paper in the rearward movement thereof, a cam lever pivotally connected to said reciprocatory device, means connecting said shaft with said cam lever whereby it is rocked to engage said gripping member with said sheet in the forward movement of said reciprocatory device, and means for preventing the rearward movement of said sheet by said reciprocatory device.

6. In a machine of the character described, the combination with a cap forming mechanism comprising a rotary crank shaft, of stock feeding mechanism adapted for carrying a sheet of material step by step to said cap forming mechanism, said stock feeding mechanism comprising a reciprocatory gripping device having means for automatically disengaging it from said sheet of material and means for reciprocating it as well as effecting its engagement with said sheet of material in the forward feeding movement, and a printing mechanism adapted for printing successive sections of said sheet while stationary between its step by step movements, said printing mechanism comprising a stationary plate under which said sheet is carried on its way to said forming mechanism, an oscillatory printing form above which said sheet is carried on its way to said forming mechanism, means for inking said printing form and means for actuating said printing form and inking means in synchronous relation, said printing means comprising a stationary and an oscillatory arm, a toggle mechanism connecting said arms, an oscillatory arm connected with said toggle mechanism to operate the latter and means operated by said crank shaft for operating said oscillatory arm last named.

In testimony whereof I have hereunto set my name this sixth day of May, 1920.

CHAS. A. GARRETT.
